UNITED STATES PATENT OFFICE.

NELSON C. OVAITT, OF DETROIT, MICHIGAN.

SOUND-REPRODUCING NEEDLE.

Substitute for application Serial No. 228,605, filed April 15, 1918. This application filed July 10, 1920.
Serial No. 395,281. Renewed March 3, 1924.

To all whom it may concern:

Be it known that I, NELSON C. OVAITT, a citizen of the United States of America, residing at Detroit, in the county of Wayne 5 and State of Michigan, have invented certain new and useful Improvements in Sound-Reproducing Needles, of which the following is a specification, reference being had therein to the accompanying drawings.

10 This invention relates to sound reproducing needles and refers more particularly to needles of the type used in phonographs or similar musical playing devices, the same being a substitute for the subject 15 matter of applicant's prior application filed April 15, 1918, Serial No. 228,605.

In phonographs or talking machines it is customary to employ a needle which travels in the groove of a record and there 20 has been developed a needle known as the tungsten or semi-permanent needle. Said needles, however, are defective, in that after they have been used a few times the friction between the needle and the record tends 25 to wear the point of the needle flat on one side; then if the needle is removed and again re-inserted in the instrument it will not accurately reproduce unless put back into the holder in exactly the same position 30 that it was when originally used. As such needles are usually provided with a cylindrical shank, it is extremely difficult to return the needle to its exact position.

The present invention particularly contemplates an improved needle construction 35 wherein the needle is automatically positioned in the holder and can thus be removed and re-inserted numerous times without interfering with the sound reproducing qualities of the mechanism. A further 40 very important feature of the invention is the arrangement whereby the shank of the needle is so formed that the end of the needle cannot be shoved into the seat far 45 enough to contact with the end of the seat, thus avoiding the possibility of double vibration caused by the contact of the end of the needle with the seat. Other objects of the invention are to provide a construction 50 whereby needles of the type now on the market can be economically formed or constructed to automatically position themselves in the holders; and in general to provide a new and improved needle construction 55 of the character above referred to.

In the drawings:

Figure 1 is a perspective view of a sound-box of a phonograph, showing one of the needles in use;

Figure 2 is an enlarged detail view of the 60 needle;

Figure 3 is a cross-section on the line 3-3 of Figure 2; and

Figure 4 is a view showing the manner in which the end of the needle is automatically kept out of contact with the end of 65 the seat.

Describing in detail the particular embodiment of my invention shown in the drawings, A designates the tone arm of a 70 sound reproducing device, such as a phonograph, and B the sound-box which is pivotally connected at C to the tone arm and is provided with a holder D which has a triangular seat E into which the needle F is 75 inserted. The needle is locked in place by tightening up the thumb-screw G which advances the end H' of the screw H against the needle F and forces it into clamping engagement with the sides E' and E² of the 80 seat E.

Referring to the needle construction shown in detail in Figure 2, the needle F comprises a main body or shank portion K in which there is suitably secured a fine 85 playing point L. In previous constructions the shank K has been formed as a cylinder so that it could be inserted into the seat E in any one of a number of positions. While the type of needle shown and described is 90 what is known as semi-permanent, it is often desirable to remove it so that certain records can be played by fiber or other needles, after which the semi-permanent needle is 95 returned for further use. By my novel construction the tungsten needle can be taken out and returned and upon its return will be automatically arranged with reference to the holder so that it will be in substantially 100 the same position that it was when originally used.

For this purpose the shank K of the needle is formed with a flat face M which is engaged by the end H' of the screw H when the thumb-screw G is turned to lock the 105 needle in the holder. While I have shown and described this face M as being flat, it is of course understood that the invention is not limited to this particular shape and resides partly in the idea of providing a 110

semi-permanent needle, of the type in which there are no locating surfaces, with a surface which will definitely position it with reference to the holder. After the needle is inserted in place it is locked by tightening up the screw H in the usual manner and the needle can be removed and re-inserted a number of times without in any way changing the relative position of the point L' to the groove N' of the disk N in which the needle point operates. Moreover in returning the needle it is only necessary to see that the flat side M is turned toward the end H' of the screw, since when the latter is tightened up it will automatically turn the needle to proper position of rotative adjustment. By this novel arrangement the needle can be removed and returned in the ordinary manner and the playing point always held in the same position with reference to the groove of the record.

As shown in detail particularly in Figure 4 the length of the flat side M is less than the distance between the bottom E³ of the seat E and the end H' of the screw H. Therefore, even though the needle is shoved in as far as the flat side will permit, the end K' of the shank K will be held out of contact with the end E³ of the seat E. This feature is important in that the needle is

not only repositioned but it is automatically held out of contact with the end of the seat.

Various changes in the details of construction can of course be made within the scope of my invention.

I claim:

1. The combination with a holder having a socket and a set-screw adapted to project into said socket, of a needle having a shank flattened on one side, said flattened side being adapted to be engaged by the end of said set-screw, the length of said flattened side being limited so as to prevent the end of the needle from reaching the end of the socket when the set-screw is in engagement with said flattened side.

2. The combination with a holder having a socket and a set-screw adapted to project into said socket, of a needle having a shank provided with a locating surface, said locating surface being adapted to be engaged by the end of said set-screw, the length of said locating surface being limited whereby the needle upon removal from the holder can be automatically returned to the same position in the holder when the set-screw is adjusted.

In testimony whereof I affix my signature.

NELSON C. OVAITT.
